UNITED STATES PATENT OFFICE.

WALTER C. BECKWITH, OF FOSTORIA, OHIO.

DEVICE FOR RAISING SUNKEN VESSELS.

1,331,610.

Specification of Letters Patent. Patented Feb. 24, 1920.

Application filed March 27, 1919. Serial No. 285,515.

To all whom it may concern:

Be it known that I, WALTER C. BECKWITH, a citizen of the United States of America, residing at Fostoria, in the county 5 of Seneca and State of Ohio, have invented certain new and useful Improvements in Devices for Raising Sunken Vessels, of which the following is a specification.

My invention relates to method and apparatus for raising sunken vessels and has for its object to provide a simple and effective means for equalizing and relieving the strain 10 on lifting and hauling cables and also to do away with the necessity of employing power 15 or lifting engines.

Great difficulty has been experienced in raising sunken vessels due to the fact that the lifting cables employed were incapable of withstanding the strain placed upon 20 them, it frequently happening that where one cable was subjected to a greater strain than the others, it would snap, thus throwing an added weight upon the others with the result that they would all give away. 25 This is obviated by my invention.

Other and further objects will be in part described and in part obvious as the specification is proceeded with.

In the accompanying drawings forming 30 part of this specification:

Figure 1 is a perspective view showing my invention in operation;

Fig. 2 is a plan view;

Fig. 3 is a side elevation of a ship partly 35 broken away to show the grooved plate or guide over which the strain equalizing cable runs;

Fig. 4 is a sectional view on the line 4—4 Fig. 3;

Fig. 5 is a detail perspective view of the 40 grooved plate or guide;

Fig. 6 is a detail view of the connection 45 between the strain equalizing cables, and the lifting cables, and

Fig. 7 is a detail view of the sheave lock.

Referring more particularly to the drawings in which like reference numerals refer to corresponding parts throughout the several views, 1 and 2 denote a pair of floating 50 bodies, preferably ships of conventional construction, anchored above a sunken vessel 3, by suitable moorings 4. In actual practice the ships 1 and 2 are preferably placed side by side, slightly spaced apart, the space 55 between the ships being preferably directly

over the sunken vessel to be raised. While only two ships are shown any number could be employed, placed side by side in rows.

Attached to one side (the off side) of each of the ships 1 and 2 is what may be termed 60 an endless strain equalizing cable 5. These cables run over sheaves or pulleys 6, mounted upon the decks of the ships, down through openings 7, and around the grooved or channeled plate or guide members 8. 65 These plates 8 which are preferably U-shaped in outline and in cross section, are suitably anchored to the uprights or beams 9 forming part of the framework of the ship's sides. A stiffening plate or brace 10. 70 reinforces that portion of the ship's deck between and slightly beyond the openings 7 therein.

Each strain equalizing cable 5 carries a plurality of blocks and tackles 11, including lifting cables 12 and 13, the cables 5 passing through sheaves or pulleys 14, as best illustrated in Fig. 2. The cables 13 are secured at one end to the eyes 15, then pass over the sheaves or pulleys 16, 17 and 18, 80 then across the deck of the ship 1 or 2 as the case may be. The cables 12, which are secured to the eyes 19 pass across the deck and thence downwardly over the sheaves or 85 pulleys 20.

In practice the ships 1 and 2, or other floating bodies are brought into proximity one to the other and preferably side by side, as illustrated in Figs. 1 and 2. The free ends of the cables 13 are then passed across 90 the space between the ships and secured to the far or off side of the opposing ship in any suitable manner as at 21. The free ends of the cables 12 are then made fast in any approved manner preferably to opposite 95 sides of the sunken vessel to be raised.

If the ships 1 and 2 are now forced apart by means of the moorings 4, or should they be tilted or rocked on their keels in opposite directions by the shifting of ballast, the 100 cables 12 and necessarily the sunken vessel 3 will be raised a distance corresponding to the movement of the ships. This operation can be repeated an indefinite number of times without again lowering the sunken 105 vessel, merely by locking the cables 12 and 13 to the sheaves 20 and 17 respectively, by means of the lock 22, and adjusting the fastening means at 19 and 21 to take up the slack in the free end of cables 12 and 13 110.

which results when the ships assume their original or normal position.

It will be noted that any abnormal strain placed on one or more of the lifting cables

- 5 12 and 13 due to an uneven separation of the ships 1 and 2, or to other causes such as the rocking and tossing of the ships, the strain equalizing cable will give at the points where excessive strain is applied un-
10 til all the lifting cables are taut and under full load.

The use of the U-shaped plate or guide members 8 for attaching the endless cables 5 permits of an even distribution of strain over a considerable portion of the ship, thus reducing to a minimum the danger of portions of the ship's frame giving away under the enormous strains to which they are subjected.

- 15 20 It will of course be understood that the cables 5 will be relatively larger than the lifting cables and that the size of the latter may vary according to the predetermined load which they will be called upon to carry.

Having thus described my invention, what I claim is:

- 25 30 35 1. An apparatus for raising sunken vessels, comprising a pair of spaced buoyant bodies, channeled plates secured to said buoyant bodies, endless cables running over said channeled plates, a plurality of blocks and tackles slidably connected to said endless cables, each block and tackle comprising a pair of lifting cables, one cable of each pair adapted to be connected at its free end

to the opposing buoyant body and the other cable of each pair adapted to be connected at its free end to the sunken vessel.

2. An apparatus for raising sunken ves- 40 sels, comprising two or more buoyant bodies adapted to be anchored side by side over the vessel to be raised, endless cables on said buoyant bodies, a plurality of pairs of lifting cables, tackle blocks slidably connecting 45 said pairs of cables to said endless cables, one of said lifting cables adapted to extend across the deck of and be secured to the off side of the opposing buoyant body, and the other cable of each pair being adapted to 50 be connected to the sunken vessel to be raised whereby the separation of said buoyant bodies exert a strain on said lifting cables and causes the sunken vessel to be raised.

- 55 3. An apparatus for raising sunken vessels comprising two or more buoyant bodies, a plurality of tackle blocks for each of said buoyant bodies, endless shifting flexible means for connecting said tackle blocks to 60 said buoyant bodies, and pairs of lifting cables connected to said blocks, one of each pair adapted to be connected to the sunken vessel, and the other cable of each pair adapted to be connected to the opposing 65 buoyant body.

In testimony whereof I affix my signature in presence of two witnesses,

WALTER C. BECKWITH.
